UNITED STATES PATENT OFFICE.

WALTER S. LYTHE, OF PHILADELPHIA, PENNSYLVANIA.

TELEGRAPHIC INSTRUMENT.

Application filed July 16, 1921. Serial No. 435,153.

To all whom it may concern:

Be it known that I, WALTER S. LYTHE, a citizen of the United States, residing at Philadelphia, in the county of Philadelphia and State of Pennsylvania, have invented certain new and useful Improvements in Telegraphic Instruments, of which the following is a description.

This invention is an improved telegraphic instrument having characteristic capacities for use as a right or left hand semi-automatic or a Morse key, for simple adjustment of the dot making contacts in semi-automatic operation to correct usual defective action due to weather conditions and secure the distinct expression of characters, and for changing the semi-automatic features and regulating the operation so as to secure the strokes desired.

20 The invention, in a preferred form thereof, is embodied in the instrument specified in the following description and the accompanying drawings in illustration thereof.

In the drawings, Fig. 1 is a top plan view 25 of the instrument adjusted for semi-automatic operations induced by the right hand of the operator; Fig. 2 is a top plan view of the instrument adjusted for use as a Morse key; Fig. 3 is a top plan view of the instrument adjusted for semi-automatic operations induced by the left hand of the operator; Fig. 4 is a side elevation of the instrument in position for semi-automatic operation with the parts in the relation shown in Fig. 1; Fig. 5 is a plan view of a detached key lever with oscillatory connections; Fig. 6 is a side elevation of the instrument with the parts in the relation illustrated in Fig. 2;

Fig. 7 is a front end elevation of the instrument with the parts in the relation illustrated in Figs. 2 and 6, the operating lever being broken away; Fig. 8 is a rear end view of the instrument; Fig. 9 is a detached view of the rotary disk with its connections by which the operating lever with its connections is turned on an axis and adjustably fulcrumed, the parts being in the position for use as a Morse key; and Fig. 10 is a view similar to that shown in Fig. 9, with the lever and its connections turned to position for the semi-automatic operation as in Fig. 1.

The instrument illustrated comprises the base 1 having mounted thereon the bearing 2 fixed intermediate its ends and the bearing

3 either fixed or hinged adjacent its rear end; the insulated conducting posts 4 intermediate its ends between respective opposite sides of the bearings 2 and 3 and the insulated conducting posts 5 near its rear end on 60 opposite sides of the bearing 3 the rearwardly diverging conducting contact bars 6 each connecting a post 4 with a post 5 on the same side of the base; the insulated conducting posts 7 near the front end of the 65 base and provided with the adjustable contacts 8, and the insulated conducting post 9 between the posts 7 and provided with the contact 10, a conducting bar 40 connecting the posts 7 and 9 and being insulated from 70 the base.

A bent operating lever 11, having the contact 44 for engaging the respective contact 8 and 10 and the offset section 11' provided with the operating knob 12, passes through 75 and is fixed to a disk or circular bearing 13 which is connected by pivots or journals 14 within a ring 15, the latter being journalled in the bearing 2. The ring 15 has fixed 80 therein, parallel to its axis, a guide tube 16 provided with a longitudinal slot 16', and the tube has therein a reciprocating bolt 17 provided with a bent dog or catch 17' which extends laterally therefrom through the slot 85 into position for engagement in the holes 2' of the bearing and holding the parts 11, 13 and 15 with their connections, respectively in three positions at the middle and the ends of a semi-circular arc, a coiled spring 18 disposed on the bolt between its head and 90 its guide tube acting to effect the automatic engagement of the catch with the holes therefor.

The lever 11 has fixed to its inner end a flat spring 19 which connects it with a bearing 20. A pair of parallel rods 21 have their inner ends held in the bearing 20, (detachably if desired, by the set screw 22) and their outer ends fixed to a yoke 23, the latter having fixed thereto the pin 24 offset from 95 the axis of the lever. The bearing 3 (which may be connected by the hinge 3' to the base 1 and held in erected position by a spring 41) comprises a ring 3^a having a bar 3^b extending from its top through its 100 centre to a rounded terminus and an oppositely disposed rounded projection 3^c, with a passage 3^d between them. The pin 24 projects into or through the ring 3^a and is movable, by turning the lever 11, to a po- 110

sition in the space 3^a between the parts 3^b and 3^c or to positions on either side thereof at right angles thereto.

A weight 25 is adjustable along the rods 21 and is held in the desired position by a set screw 43. The weight 25 carries an adjustable screw 27 which is set in the desired position by the nuts 27', and the screw has fixed on one end thereof a coiled spring 28 which carries a contact 29. The contact 29 is adapted for engagement with either contact bar 6 at various positions along the length thereof by the adjustment of the weight 25 along the rods 21 and the adjustment of the lever 11 by turning it about its axis.

The ring 15 has fixed thereto, parallel to its axis on opposite sides thereof, the bars 30 and 31. The bar 30 is provided with the 20 adjustable screw 32 for engaging and limiting the movement of the lever 11 in one direction and the bar 31 is provided with the adjustable screw 33 for limiting the movement of the lever in the other direction. 25 Adjustable screws 34 and 35 in opposite ends of the bar 31 on opposite sides of the ring 15 carry coiled springs 36 and 37 which act oppositely to retract the lever from its position in engagement with the screw 33 toward or in engagement with the screw 34.

A segmental plate 42, fixed to the bearing 2, is adapted for engaging the parts 16 and 31 to stop the rotation of the lever 11 in its position for the right and left hand semi-35 automatic operations.

A switch lever 38, having the fulcrum 39 on the base 1, is movable into and out of engagement with the plate 40 to connect and disconnect it and the posts 7 and 9 relatively 40 to the base.

Conductors 45 and 46 pass through a side of the base 1, respectively, to an electrical connection therewith and with the posts 4, 7 and 9, these conductors being connected 45 through the base to make a closed circuit by throwing the lever 38 into contact with the plate 40.

In operation, when the instrument is to be used in semi-automatic operation induced 50 by the thumb of the right hand of the operator, the parts being in the position shown in Figs. 1 and 4, the movement of the knob 12 to the right throws the contact 29 into engagement with the left hand bar 6 and this 55 contact is oscillated with the production of the desired number of dots rapidly, to make and break the circuit repeatedly, depending on the length of time the knob is held to the right. When the operator withdraws his 60 thumb from the knob 12, the springs 36 and 37 act on the lever 11 and through the intermediate oscillator to withdraw the contact 29, so that it will not engage the adjacent bar 6, and to throw the contact 44 to- 65 ward the contact 8 of the left hand post 7,

the first finger of the right hand being applied to the knob 12 to press the contact 44 against the contact 8 to produce the desired dash or dashes. In this operation the pin 24 oscillates within the ring 3, to the left of the bar or finger 3^b, by which the arc of the movement of the oscillator is limited. If, owing to weather conditions or the touch of the operator, for instance, the contact between the parts 6 and 29 does not produce 75 the dots with sufficient clearness and loudness, the oscillator's weight 25 is moved along the rods 21 to adjust the length of the stroke and the force of the blow, with resulting change in the character of the contact 80 and the effect in transmitting.

When the instrument is to be used in semi-automatic operation induced by the thumb of the left hand of the operator, the bolt 17 is pressed in, the catch 17' is disengaged 85 from the bearing 2, and the lever 11 is turned through a half circle to the position illustrated in Fig. 3, when the pin 24 lies to the right of the bar 3^b, the contact 29 acts upon the right hand bar 6 and the contact 44 acts on the right hand contact 8 similarly to the operations previously described.

When it is desired to operate the instrument as a Morse key, the lever 11 is set in the position illustrated in Figs. 2, 6 and 7, 95 the pin 24 being in the position illustrated in Fig. 8. Now the pressure of the finger of the operator upon the knob 12 engages the contact 44 with the contact 10, to make dot or dash as may be required, the springs 100 36 and 37 acting to disengage these contacts as in withdrawing the contact 44 from the corresponding contact 8.

Having described my invention, I claim:

1. A transmitting telegraphic instrument 105 having a base, a lever fulcrumed relatively to said base and adapted to be oscillated in different planes, said lever having on opposite sides of its fulcrum a relatively fixed contact and a relatively oscillatory contact, a plurality of contacts carried by said base and adapted respectively for engagement by the relatively fixed contact of said lever when oscillating in different planes, and a pair of contacts carried by said base and adapted respectively for engagement by said relatively oscillatory contact when said lever is moved laterally in different positions thereof.

2. A transmitting telegraphic instrument 120 having a base, a bearing mounted thereon, a device journaled in said bearing, a lever fulcrumed in said device, said lever having a contact on one side of its fulcrum and on the other side thereof an oscillator provided with a contact, a contact device carried by said base for cooperation with said contact first named in the vertical movement of said lever, contact devices carried by 125 said base on opposite sides of said lever for 130

engagement with said contact first named when said lever is moved laterally in opposite directions in different positions thereof, and contact devices carried by said base on opposite sides of said oscillator for engagement with said contact second named when said lever is operated laterally in opposite directions in different positions thereof.

- 10 3. A transmitting telegraphic instrument comprising a base provided with a bearing, a device journalled in said bearing, a lever fulcrumed in said device, means carried by said device for limiting the oscillatory movements of and positioning said lever, means for fixing said journalled device in different positions and holding said lever in positions for oscillating laterally or vertically, and contact devices disposed on opposite sides

of said lever and a contact device disposed 20 beneath said lever, with which contact devices said lever is adapted to engage when oscillated vertically or laterally in different positions of said journalled device.

4. A transmitting telegraphic instrument 25 comprising, in combination with contact devices, a journalled operating lever provided with an oscillator having a contact, means for fixing said lever in different positions for movements in vertical and horizontal 30 planes, a pin carried by said oscillator eccentrically to the axis of revolution of said lever, and means for engaging said pin in different positions of said lever to control the action of said oscillator.

In testimony whereof I have hereunto set my name this 21st day of June, 1921.

WALTER S. LYTLE.
